(57) **CLAIM**

The ornamental design for a wearable strap with linking member, as shown and described.

DESCRIPTION

FIG. 1 is a top perspective view of a design for a wearable strap with linking member;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Any broken lines showing portions of the design are for illustrative purposes or to show environmental structure or boundaries that form no part of the claimed design. It shall be understood that the design is shown having a symbolic break but the portions not shown between break lines form no part of the claimed design.

1 Claim, 5 Drawing Sheets
